UNITED STATES PATENT OFFICE.

CLAYTON W. HODGEN, OF KANSAS CITY, KANSAS.

WINDOW FRAME.

1,407,536.

Specification of Letters Patent. Patented Feb. 21, 1922

Application filed July 8, 1918, Serial No. 243,960. Renewed December 13, 1920. Serial No. 430,556.

To all whom it may concern:

Be it known that I, CLAYTON W. HODGEN, a citizen of the United States, residing at Kansas City, in the county of Wyandotte and State of Kansas, have invented certain new and useful Improvements in Window Frames, of which the following is a specification.

This invention relates to building construction and more particularly to window frames.

One of the objects of this invention resides in the provision of a window frame of the box frame type and of such construction that the plastic coating on the exterior of a building will have those edges thereof which contact with the window frame disposed within grooves in the window frame.

Another object of this invention resides in the provision of a window frame of such construction that the stucco surface on a building will be keyed where it terminates around a window.

A still further object of this invention resides in the provision of a window frame of such construction that it forms a ground for the plaster and also the jamb block for the casing.

With these and other objects in view, this invention resides in certain novel features of construction and arrangement of parts to be more particularly set forth in the specification herewith and pointed out in the appended claims, it being understood that the right is reserved to make such departures from the present disclosure as come within the scope of the claims.

In the accompanying drawing:—

Figure 1 is an exterior view of a portion of a building showing a window frame of the present construction in a fixed position;

Figure 2 is an enlarged sectional view on line 2—2 of Figure 1 with the central portion of the window broken away;

Figure 3 is a horizontal sectional view of one side of the window.

In the present embodiment of this invention the letter B represents a portion of a building which is preferably coated with a stucco finish S. In constructing buildings of the above character, the previous method of applying the stucco finish to the surface surrounding windows and doors has proven unsatisfactory for the stucco finish would

peel off where it contacted with the window frame and eventually cause the entire surface to release its hold on the wall. So in order to eliminate these disadvantages and maintain a permanently secured finish, the window frame, which is of the box frame type, and which is adapted for use in brick, concrete or stone walls, is provided with inner jamb sections F, outer jamb sections 7 disposed parallel therewith, and outer sections 6 which respectively connect the adjacent jamb sections F and 7. The outer sections 6 preferably have their outer edges abutting against the inner sides respectively of the adjacent sections 7, and the outer sides of the sections 6 extend outwardly respectively beyond the outer edges of the adjacent sections 7, thus providing grooves 5 along the outer side and top corner edges of the box frame.

From the foregoing it will be understood that, as the outer edges of the sections 6 project beyond the adjacent edges of the outer jamb sections 7, as does the wall B, channels will be formed by the wall with the sections 6 and 7 at the corner edges of the frame adapted to receive the edges of a sheet of plastic wall covering, such as stucco and plaster.

In order to avoid a similar peeling action of the plaster P adjacent the window, the section 7 of the window frame is extended inwardly approximately the thickness of the plaster and the interior trim 8 is secured to said section 7 in such manner that the plaster will terminate behind the interior trim E where it is protected by the overlapping edge E of said interior trim.

In view of having successfully produced a window frame for preventing the peeling action of the stucco finish and plaster that abuts the window frame, it is apparent that door frames or the like can be so employed for similar purposes and it is desired to herein disclose the intention of such adaptation should circumstances arise where its necessity occurred.

By providing a box frame of the kind described with the grooves 5 at the outer vertical and top corners of the box frame, the frame may be inserted in the opening in the wall after the stone, brick or concrete work has finished and the wall has been laid. With the ordinary construction of box

frame, the frame must be set and the wall built to it in order to get a tight joint at the top and sides.

After the wall has been laid and the openings provided therein for the doors and windows, my improved box frame with the inner casing sections 8 detached therefrom is set in the wall with the outer jamb sections 7 projecting inwardly beyond the wall an 10 amount corresponding to the thickness of the plaster. The frame is held in position in any desired manner. The stucco finish S is then applied to the outer side of the wall and fills the grooves 5 at the outer corners 15 of the frame, as shown in Figs. 2 and 3. Tight joints are thus afforded at the outer corners of the sides and top of the box frame.

The plastering P is then applied to the inner side of the wall and against the jamb 20 sections 7, after which the inner casing sections 8 are applied in the usual manner so as to extend over the plaster.

The box frame provides the usual runway for the sash weights, as shown in Fig. 3, the 25 outer jamb sections 7 dispensing with the employment of the usual jamb blocks.

With this invention fully set forth it is manifest that a window frame is produced which will be cheap of manufacture and 30 readily adapted to perform the functions intended.

Having thus described this invention what I claim is:—

1. The combination with a wall having an opening, of a frame mounted in said opening and having a jamb section, and a section at right angles to the jamb section arranged to form with the wall and the jamb section a channel adapted to receive the edge of a sheet of plastic wall covering, substantially as set forth. 35

2. The combination with a wall having an opening, of a box frame mounted therein comprising inner jamb sections and outer jamb sections and sections connecting the 40 jamb sections respectively and arranged to form with the outer jamb section and the wall channels adapted to receive the edges of a sheet of plastic wall covering, substantially as set forth. 50

3. The combination with a wall having an opening, of a frame mounted in said opening and having a jamb section and having a section abutting at one edge against the jamb section, said edge projecting beyond 55 the adjacent edge of the jamb section and forming with the jamb section and the wall a channel adapted to receive the edge of a sheet of plastic wall covering, substantially as set forth. 60

In testimony whereof I affix my signature.

CLAYTON W. HODGEN.
